UNITED STATES PATENT OFFICE.

JOHN W. RUHL, OF MIFFLINBURG, PENNSYLVANIA, ASSIGNOR OF ONE-HALF
TO DAVID L. RUHL, OF SAME PLACE.

GATE.

SPECIFICATION forming part of Letters Patent No. 479,665, dated July 26, 1892.

Application filed March 16, 1892. Serial No. 425,139. (No model.)

To all whom it may concern:

Be it known that I, JOHN W. RUHL, a citizen of the United States, residing at Mifflinburg, in the county of Union and State of Pennsylvania, have invented a new and useful Gate, of which the following is a specification.

The invention relates to improvements in gates.

10 The object of the present invention is to simplify and improve the construction of tilting gates and to provide one which may be readily opened or closed from either side of it at a distance therefrom to avoid dismounting or leaving a vehicle.

15 The invention consists in the construction and novel combination and arrangement of parts hereinafter fully described, illustrated in the accompanying drawings, and pointed out in the claim hereto appended.

20 In the drawings, Figure 1 is a perspective view of a gate. Fig. 2 is a vertical sectional view.

25 Like numerals of reference indicate corresponding parts in both the figures of the drawings.

30 1 designates a tilting gate, which is pivotally mounted between posts 2, and which is provided with a rearwardly-projecting triangular extension 3, having a weight 4, whereby the gate is counterbalanced and may be readily tilted and opened by pulling-ropes 5. The front end of the gate is provided with a spring-actuated latch 6, arranged to engage a horizontally-disposed keeper 7 or a latch-post 8. The upper end of the latch is connected by a cord or rope 9 with a vertically-disposed latch-

lever 10, which is fulcrumed on the gate and is connected below its pivotal point by a latch-rope 11 with the pulling-rope 5. The pulling-ropes extend vertically from the gate and over a pulley 13 at the top of the latch-post 8 and thence over pulleys 14 of uprights 15, arranged on opposite sides of the gate. By pulling one of the ropes 5 the latch is released from engagement with the keeper and the gate is raised sufficiently to cause the weight 4 to act and carry the gate to a vertical position. When the gate is being closed, the weight serves to retard it and to counterbalance it to prevent injury to it.

It will be seen that the gate is simple and comparatively inexpensive in construction and is capable of being readily operated.

What I claim is—

35 The combination of the posts, a gate pivotally mounted between the posts and provided with a weighted inverted triangular extension projecting rearwardly from it, rigid with it, and forming a part of it, a latch arranged at the front of the gate, a vertically-disposed lever fulcrumed on the gate and having its upper end connected with the latch, and operating-ropes connected with the lower end of the lever and adapted to release the latch and lift the gate, substantially as described.

In testimony that I claim the foregoing as my own I have hereto affixed my signature in the presence of two witnesses.

JOHN W. RUHL.
